[57] CLAIM

The ornamental design for a handle for magnifier lens, as shown and described.

DESCRIPTION

FIG. 1 is a perspective view from the top, front, and right side of a handle for magnifier lens showing our new design;

FIG. 2 is a top plan view thereof;

FIG. 3 is a bottom plan view thereof;

FIG. 4 is a front elevational view thereof;

FIG. 5 is a side elevational view thereof, the opposite side is a mirror image of the side shown;

FIG. 6 is a rear elevational view thereof; and,

FIG. 7 is a reduced perspective view thereof, the broken lines are for illustrative purposes only and form no part of the claimed design.
